UNITED STATES PATENT OFFICE.

HERBERT R. DRURY, OF WILLOUGHBY, OHIO.

DESIGN FOR AN ANTIGLARE DEVICE FOR AUTOMOBILE-HEADLIGHTS.

57,619.

Specification for Design.

Patented Apr. 26, 1921.

Application filed September 7, 1920. Serial No. 408,792. Term of patent 7 years.

To all whom it may concern:

Be it known that I, HERBERT R. DRURY, a citizen of the United States, residing at Willoughby, in the county of Lake and State of Ohio, have invented a new, original, and ornamental Design for an Antiglare Device for Automobile-Headlights, of which the following is a specification, reference being had to the accompanying drawings, forming a part hereof.

Figure 1 is a perspective view; Fig. 2, an elevational view; and Fig. 3 a sectional view as indicated by the line 3—3 of Fig. 2, of an antiglare device for automobile headlights showing my new design.

I claim:—

The ornamental design for an antiglare device for automobile headlights as shown.

HERBERT R. DRURY.
